(57) **CLAIM**

The ornamental design for a wireless audio player for vehicle as shown and described.

DESCRIPTION

FIG. 1 is a perspective view of a wireless audio player for vehicle showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings are for the purpose of illustrating portions of the wireless audio player for vehicle that form no part of the claimed design.

1 Claim, 8 Drawing Sheets
